[57] CLAIM

The ornamental design for a nestable tray for bottles, as shown and described.

DESCRIPTION

FIG. 1 is a top perspective view of a nestable tray for bottles showing our new design;

FIG. 2 is a bottom perspective view thereof;

FIG. 3 is a top plan view thereof;

FIG. 4 is a bottom plan view thereof;

FIG. 5 is a front elevational view thereof; the rear elevational view being a mirror image;

FIG. 6 is a right end elevational view thereof; the left end elevational view being a mirror image;

FIG. 7 is a top perspective view thereof, the broken line showing of a nested tray is for illustrative purposes only and forms no part of the claimed design;

FIG. 8 is an enlarged perspective section taken along line 8—8 of FIG. 3; and,

FIG. 9 is an enlarged elevational view taken along line 9—9 of FIG. 3.

FIG. 3

FIG. 4

FIG. 5

FIG. 6

FIG. 7

FIG. 8

FIG. 9
